UNITED STATES PATENT OFFICE.

JESSE J. HEAP, OF NEW YORK, N. Y., ASSIGNOR TO UNION SPECIAL MACHINE COMPANY, OF CHICAGO, ILLINOIS, A CORPORATION OF ILLINOIS.

FOLDER FOR SEWING MACHINES.

1,412,001.

Specification of Letters Patent. Patented Apr. 4, 1922.

Application filed March 20, 1918. Serial No. 223,571.

To all whom it may concern:

Be it known that I, JESSE J. HEAP, a citizen of the United States, residing at New York, in the county of Kings, State of New York, have invented certain new and useful Improvements in Folders for Sewing Machines, of which the following is a description, reference being had to the accompanying drawing and to the figures of reference marked thereon.

The invention relates to new and useful improvements in folders for sewing machines and more particularly to an adjustable folder for folding and directing the center plait or facing strip which is to be stitched to the outside of a shirt front.

Sewing machines adapted to stitch plaits or facing strips to a shirt front often have different spaces between the needles and an object of the present invention is to provide a folder which is capable of ready adjustment so as to properly direct the facing strip or plait to the needles as they may be set in any particular machine to which the folder is applied.

A further object of the invention is to provide an adjustable folder for directing a facing strip or plait which is capable of adjustment so that the margin from the line of stitching to the adjacent folded edge of the strip may be varied with different classes of material or character of work to meet the requirements of different manufacturers.

A further object of the invention is to provide a folder for directing a facing strip or plait which may be adjusted at both ends to meet the requirements of different widths of strip and different characters of material.

These and other objects will in part be obvious and will in part be hereinafter more fully disclosed.

In the drawings,

Figure 1 is a view of a sewing machine having my improved folder applied thereto, the section being a vertical section centrally through the folder and through the sewing machine;

Fig. 2 is a plan view of the folder for directing and folding the facing strip or plait; 50

Fig. 3 is a sectional view on the line 3—3 of Fig. 2;

Fig. 4 is a similar view but showing the folder adjusted for a wider strip;

Fig. 5 is a sectional view on the line 5—5 55 of Fig. 2;

Fig. 6 is a perspective view of the supporting bracket for my improved folder;

Fig. 7 is a perspective view of one section of my improved folder; 60

Fig. 8 is a perspective view of the other section of the folder;

Fig. 9 is a detail showing the position of the end of the folder relative to the presser foot and the needles; 65

Fig. 10 is a view showing more or less diagrammatically the position of the facing strip to the fabric and the needles when the parts are adjusted so that a relatively narrow margin is provided at each side of the 70 facing strip between the line of stitching and the folded edge of the strip;

Fig. 11 is a similar view with the folder adjusted so as to form wider margins.

In Figures 10 and 11 of the drawings, I 75 have shown more or less diagrammatically the body fabric at F which may be a portion of the front of a shirt to which a facing strip is to be attached. In these figures of the drawings I have shown the outer facing 80 strip at f and the under facing strip at f'. The facing strips are joined together and to the body fabric F by lines of stitching indicated in these figures at n and n'. It will be noted that the outer facing strip has 85 one of its edges folded in forming a margin m between the line of stitching n and the adjacent fold in the outer facing strip. There is also a margin m' between the line of stitching n' and the adjacent folded edge 90 in the outer facing strip.

In Figure 10, it will be noted that these margins m and m' are relatively small while in Figure 11, the margins are relatively large. The position of the needles is indicated in these figures by the lines of stitch-

ing n and n' . Facing strips or plaits are usually stitched to a shirt front on a machine provided with two needles, which needles are widely spaced so as to simultaneously 5 form the line of stitching n and n' , joining the facing strips and joining the facing strips to the body fabric. These needles in machines adapted for this purpose sometimes vary slightly in the distance which 10 they are set apart.

The present invention is directed to a folder which is particularly adapted for folding and directing the outer facing strip, which folder is formed so that it may be 15 adjusted to properly direct the strip to the needles with the spacing between the needles as found in the machine to which the folder is attached. The folder is also capable of adjustment so that the margin between the 20 lines of stitching and the respective adjacent folded edges in the facing strip may be varied, as above noted.

Referring more in detail to the drawings, I have shown my improved folder applied 25 to a sewing machine having a work support 1 on which the fabric is held by means of a presser foot 2. The fabric is fed across the work support by a feed dog 3. The stitching mechanism includes two spaced needles 4 30 and 5. These needles are carried by a needle bar 6. Cooperating with each needle is a looper 7 so that the two independent lines of stitching are formed. These parts are all of the usual construction and will not need 35 any further description. It may be noted that in this connection, the needles 4 and 5 are carried by a needle head at the lower end of the needle bar 6 and that the distance between these needles 4 and 5 may vary 40 slightly in different machines.

Attached to the work support is a guide 8 for the under facing strip f' . This guide is similar to that shown in the patent to De Nike, 790,560, granted May 23rd, 1905, and 45 forms no part of the present invention, except as it is used to direct the under facing strip so that it may be simultaneously stitched with the outer facing strip. The edges of this under facing strip are usually 50 well within the marginal edges of the outer facing strip.

My invention is directed particularly to the folder for directing and folding the outer facing strip or plait and the folder is indicated at 9 in the drawings. Said folder is mounted on a shank 10 which is carried by an arm 11. The arm 11 is mounted to turn freely on the supporting stud 12. The supporting stud 12 is rigidly carried by a 60 bracket 13 which is secured to the head of the machine by suitable screws passing through openings 14 in said bracket. A collar 15 is adjustably fixed to the stud 12 and has a stop arm 16 against which the arm 65 11 rests when the folder is in operative rela-

tion to the presser foot and stitching mechanism. Said stud 12 has a second collar 17 provided with a stop arm 18 adapted to limit the upward movement of the arm 11. The arm 11 has a split sleeve connection with the 70 stud 12 and a screw 19 operates to cause the arm to frictionally grip the stud.

The folder 9 proper, is formed of two sections 9^a and 9^b. The section 9^a is fixed to the shank 10 by suitable screws 20 and 21. 75 This shank extends underneath both of the sections of the folder. The section 9^b is also fixed to the shank by screws 22 and 23. The shank is formed with slots 24 and 25 which are adapted to receive respectively the screws 80 22 and 23. These slots extend in lines at right angles to the center line of the folder so that the section 9^b may be adjusted laterally or in a direction at right angles to the center line through the folder, by loosening 85 the screws 22 and 23 and moving the section on the supporting shank.

The section 9^a has a lower guiding plate 26 and an upper overhanging guiding plate 27. The two plates are formed integral 90 at their side edges and are gradually bent from a point adjacent the receiving end of the folder toward the delivery end of the folder so as to fold underneath the edge of the strip guided thereby. At the delivery 95 end of the folder there is an inner guiding section 28 which is formed as a part of the plate 26 and the guiding recess extending about this section 28 folds the side edge of the facing strip or plait underneath the same, 100 as clearly shown in Figures 3 and 4 of the drawing. The section 9^b is formed with an under guiding plate 29 and an upper overhanging plate 30. These plates are integral 105 at their side edges and are shaped similarly to the plates 26 and 27, so as to fold underneath the opposite side edge of the facing strip or plait. At the delivery end there is a guiding section 31, similar to the guiding section 28.

At the receiving end of the folder there is a plate 32 (see Figs. 5 and 7). This plate 32 is rigidly secured to the section 9^a by screws 33 and 34. It is also rigidly secured to the section 9^b by screws 35 and 36. The screws 35 and 36 pass through elongated slots 37 parallel to the slots 24 and 25. The plate 26 at the receiving end is extended at 38 so as to overlap the plate 29. Said overlapped section 38 is formed with a slot 39 through which a screw 40 extends. By loosening the screws 22, 23, 35, 36 and 40 the whole section 9^b may be moved bodily away from the section 9^a. The plate 30 has an arm 30^a which extends over the plate 27 110 at the receiving end thereof. This arm 30^a overlies the space between the plates and prevents the material from bending, buckling or working up between the plates. At the delivery end of the folder, the plate 27 115

has an extension 30^b which overlies the plate 30 and likewise prevents the material at the delivery end of the folder from buckling, or bending or working up between the plates.

5 The plates 27 and 30 at the receiving end of the folder are set back from the ends of the plates 26 and 29. The plates 26 and 29 are formed with upturned sections 41, which are adapted to guide the side edges of the 10 facing strip as it passes into the folder, said facing strip being received flat and unfolded. As it passes along the folder the side edges of the facing strip or plait will be gradually turned underneath, as clearly 15 shown in Fig. 3 of the drawings and as this facing strip leaves the folder its side edges will be folded and they will be guided by the folder to the needles. The arm 11 may be adjusted endwise of the stud 12 by shifting 20 the collars 15 and 17 carrying the stop arms. This permits the setting of the folder so as to obtain the desired margin m' between the line of stitching n' and the adjacent folded edge of the facing strip. The 25 section 9^b of the folder is then set in the manner above described so as to obtain the proper margin m between the line of stitching n and the adjacent folded edge in the facing strip or plait. In other words, by 30 this adjustment of the folder these two margins m and m' may be made alike and may be varied within certain limits, as desired.

It sometimes happens that the facing strips vary slightly in width and my improved folder may be readily adjusted so as to accommodate strips of different widths by the adjustments above described.

The essential features of my improved folder consist in the bodily adjustment of 40 one section of the folder relative to the other and the shifting of the folder relative to the needles so as to secure the functions above described.

It is obvious that minor changes in the 45 details of construction may be made without departing from the spirit of the invention as set forth in the appended claims.

Having thus described my invention, what I claim as new and desire to secure by Letters Patent, is:—

1. A sewing machine including in combination, spaced needles, a folder for directing a facing strip to said needles, a bracket, an arm secured to the bracket, a shank secured to said arm and supporting said folder, said arm being adjustable on said bracket in a direction at right angles to the longitudinal center of the folder, said folder including two sections, each of which consists of spaced guiding plates shaped so as to fold underneath the side edges of the facing strip, and means for securing one of said sections to the shank, whereby the same may be adjusted bodily and laterally relative to the other section.

2. A sewing machine including in combination, spaced needles, a folder for directing a facing strip to said needles, a bracket, an arm secured to the bracket, a shank secured to said arm and supporting said folder, said arm being adjustable on said bracket in a direction at right angles to the longitudinal center of the folder, said folder including two sections, each of which consists of spaced guiding plates shaped so as to fold underneath the side edges of the facing strip, and means for securing one of said sections to the shank, whereby the same may be adjusted bodily and laterally relative to the other section, said sections having the upper guiding plates thereof throughout a greater portion of their length spaced so as to facilitate the insertion of the strip within the folder, one of said upper plates having an arm extending over the space between the plates and overlying the opposed plate.

3. A sewing machine including in combination, spaced needles, a folder for directing a facing strip to said needles, a bracket, an arm secured to the bracket, a shank secured to said arm and supporting said folder, said arm being adjustable on said bracket in a direction at right angles to the longitudinal center of the folder, said folder including two sections, each of which consists of spaced guiding plates shaped so as to fold underneath the side edges of the facing strip, and means for securing one of said sections to the shank, whereby the same may be adjusted bodily and laterally relative to the other section, said sections having the upper guiding plates thereof throughout a greater portion of their length spaced so as to facilitate the insertion of the strip within the folder, one of said upper plates having an arm extending over the space between the plates and overlying the opposed plate.

4. A sewing machine including in combination, spaced needles, a folder for directing a facing strip to said needles, a bracket, an arm secured to the bracket, a shank secured to said arm and supporting said folder, said arm being adjustable on said bracket in a direction at right angles to the longitudinal center of the folder, said folder including two sections, each of which consists of spaced guiding plates shaped so as to fold underneath the side edges of the facing strip, and means for securing one of said sections to the shank, whereby the same may be adjusted bodily and laterally relative to the other section, said sections having the upper guiding plates thereof throughout a greater portion of their length spaced so as to facilitate the insertion of the strip within the folder, one of said upper plates having an arm extending over the space between the plates and overlying the opposed plate, said opposed plate at the delivery end of the folder having an extension overlying the plate carrying said arm.

5. A sewing machine including in combination, spaced needles, a folder for directing a facing strip to said needles, a supporting shank for said folder, means for
5 adjustably supporting said shank, whereby the folder may be adjusted in a direction at right angles to the longitudinal center of the folder, said folder including two sections constructed so as to fold underneath the side
10 edges of the facing strip, and means for

securing one of said sections to the shank, whereby the same may be adjusted bodily and laterally relative to the other section.

In testimony whereof, I affix my signature, in the presence of two witnesses.
